UNITED STATES PATENT OFFICE.

HOWARD J. KERR, OF BAYONNE, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed August 7, 1922. Serial No. 579,981.

To all whom it may concern:

Be it known that I, HOWARD J. KERR, a citizen of the United States, residing at Bayonne, in the county of Hudson and State of New Jersey, have invented a new and useful Improvement in Steam Boilers, of which the following is a specification.

My invention relates to steam boilers, and particularly to means by which a seal may be established between a furnace wall and the boiler parts to prevent the escape of gases from the furnace. The invention will be best understood from the following description and the annexed drawing, in which, 10 Figure 1 is a section through the lower part of the down-take headers of a horizontally inclined water tube boiler, which I have adopted for purposes of illustration; Fig. 2 is a section on line 2—2 of Fig. 1, and Fig. 20 3 is a view from the left of Fig. 1, with some of the parts removed or broken away.

Like reference characters indicate like parts in the several views.

Referring, now, to the illustrative form 25 of my invention, the down-take headers 10, into which extend the water tubes 11, are provided with a mud drum 12 extending below the lower ends thereof, the mud drum being connected to each of the headers 10 by a nipple 13, in the usual manner.

Between the furnace chamber and the lower ends of the headers 10, as well as the mud drum 12, is the upper portion of a furnace wall 14 which, in the form illustrated, 35 extends up to the tubes 11. Beneath the mud drum 12 is a water trough 15 connected to and supported by the boiler casing 16.

Between the wall 14 and the boiler parts is a plurality of sealing plates 17, each of 40 which, in the illustrative form, has an inwardly turned edge 18 in contact with the headers 10 and forming a closed joint therewith. The lower portion of the plates 17 is provided with a recessed end 19 which extends over one of the walls of the water trough 15.

In the illustrative form, the plates 17 are arranged edge to edge across the boiler, and are provided with overlapping portions at 50 these edges to make a tight joint and, at the same time, one which will permit relative side motion between the several plates. The plates 17 are held to the headers 10 and the mud drum 12, in the illustrative form, by loops 20 extending around the nipples 13,

with their ends extending through slotted holes 21 in the plates 17, and having nuts to draw and hold the plates 17 against the boiler parts.

The wall 14 is provided with a course of 60 tile 22 arranged to form a T-shaped slot between them, each slot receiving a T-shaped projection 23 connected to a plate 17, as shown best in Fig. 2. The slots in the tile 22 and the T-shaped projections 23 are arranged so that the tile and the plate 17 may be moved relatively in a vertical direction, while, at the same time, relative motion in a horizontal direction is prevented.

In the arrangement shown, plates 17, 70 through this contact with the headers 10 and with the wall 14, form a seal between the boiler parts and the wall to prevent leakage of gases from the furnace chamber and the tube spaces into the space outside of the 75 headers and the wall, and by reason of the connection of the plates 17 with the boiler parts and with the wall, this seal is maintained, irrespective of the relative motion between the boiler parts and the wall. For 80 instance, if the boiler parts should rise vertically, then, by reason of the slots 21 and the T-shaped connections with the course of tile 22, this motion will be permitted without disturbing the sealing relations of the plates 85 with the boiler parts and the wall. The same is true of the relation between the lower ends of the plates and the water trough 15. At the same time, by reason of the connection of the tiles 22 with the plates 90 17, the wall 14 is maintained in a vertical relation, by reason of the connection of these plates 17 to the boiler parts themselves. In other words, any motion horizontally of the boiler parts or of the wall will carry the 95 other element with it, so that the horizontal relation between the two is maintained at all times.

While I have shown my invention in connection with a boiler having individual 100 headers 10, it will be understood that it may also be applied in a similar manner to a boiler having a continuous water chamber, and in the appended claims where I have used the term "water chamber," it will be 105 understood to mean either a single water chamber or one made up of a plurality of individual headers, as in the illustrative embodiment. While I have shown my arrangement in connection with the down-take 110

headers, it will be understood that a similar arrangement may be provided beneath the up-take headers with a horizontally inclined water tube boiler.

5 It will also be understood that certain features of my invention may be used independently of other features.

I claim:

10 1. In a steam boiler, a water chamber, a wall extending upwardly between the water chamber and the boiler furnace, a plate connected to the wall and having a sliding contact with the water chamber, and a connection between the plate and the water chamber arranged to prevent relative horizontal motion and to permit relative vertical motion between the plate and the water chamber.

15 2. In a steam boiler, a water chamber, a wall extending upwardly between the water chamber and the boiler furnace, a plate connected to the wall and having a sliding contact with the water chamber, and a connection between the plate and the water chamber arranged to prevent relative horizontal motion and to permit relative vertical motion between the plate and the water chamber, said plate having a projection extending into the wall and the projection and the wall being connected to permit relative vertical motion and to prevent relative horizontal motion between the plate and the wall.

20 3. In a steam boiler, a water chamber, a wall extending upwardly between the water chamber and the boiler furnace, a plate connected to the wall and having a sliding contact with the water chamber, and a connection between the plate and the water chamber arranged to prevent relative horizontal motion and to permit relative vertical motion between the plate and the water chamber, a water trough beneath the water chamber and supported on the boiler casing independently of the wall, said plate having a sliding contact at its lower end with the water trough.

25 4. In a boiler having horizontally inclined tubes connected to headers, a mud drum beneath the headers and connected thereto, a wall extending upwardly between the boiler furnace and the mud drum, a plate between the wall and the mud drum and connected to the wall and having a sliding contact with the headers, and connections between the plate and the water chamber and mud drum arranged to permit relative vertical motion and to prevent relative horizontal motion between the headers and the plate.

30 5. In a boiler having horizontally inclined tubes connected to headers, a mud drum beneath the headers and connected thereto, a wall extending upwardly between the boiler furnace and the mud drum, a plate between the wall and the mud drum and connected to the wall and having a sliding contact with

the headers, and connections between the plate and the water chambers and mud drum arranged to permit relative vertical motion and to prevent relative horizontal motion between the headers and the plate, said plate having a projection extending into the wall and arranged to permit relative vertical motion and to prevent horizontal motion between the wall and the plate.

35 6. In a boiler having horizontally inclined tubes connected to headers, a mud drum beneath the headers and connected thereto, a wall extending upwardly between the boiler furnace and the mud drum, a plate between the wall and the mud drum and connected to the wall and having a sliding contact with the headers, connections between the plate and the water chamber and mud drum arranged to permit relative vertical motion and to prevent relative horizontal motion between the headers and the plate, and a water trough beneath the mud drum supported on the boiler casing independently of the wall, said plate having a sliding contact at its lower end with the water trough.

40 7. In a steam boiler, a water chamber, a wall extending upwardly between the water chamber and the boiler furnace, a plurality of plates extending edge to edge across the boiler between the wall and the water chamber, each plate being connected to the wall and having a sliding contact with the water chamber, and a connection between the water chamber and the plate arranged to prevent relative horizontal motion and to permit relative vertical motion between the plate and the water chamber.

45 8. In a steam boiler, a water chamber, a wall extending upwardly between the water chamber and the boiler furnace, a plurality of plates extending edge to edge across the boiler between the wall and the water chamber, each plate being connected to the wall and having a sliding contact with the water chamber, and a connection between the water chamber and the plate arranged to prevent relative horizontal motion and to permit relative vertical motion between the plate and the water chamber, each plate having a projection extending into the wall and arranged to prevent relative horizontal motion and to permit relative vertical motion between the plate and the wall.

50 9. In a boiler having horizontally inclined tubes connected to headers, a mud drum beneath the headers and connected thereto by nipples, a wall extending between the boiler furnace and the mud drum, a plurality of plates extending edge to edge across the boiler and connected to the wall, each plate having a sliding contact with the headers, and looped members extending through vertical slots in the plate and around the nipples and connected to the

plates to hold the plates in contact with the headers.

10. In a boiler having horizontally inclined tubes connected to headers, a mud drum beneath the headers and connected thereto by nipples, a wall extending between the boiler furnace and the mud drum, a plurality of plates extending edge to edge across the boiler and connected to the wall, each plate having a sliding contact with the headers, looped members extending through vertical slots in the plate and around the nipples and connected to the plates to hold the plates in contact with the headers, said plates having projections extending into the wall and arranged to permit relative vertical motion and to prevent relative horizontal motion between the plates and the wall.
- 15 20. 11. In a boiler having horizontally in-

clined tubes connected to headers, a mud drum beneath the headers and connected thereto by nipples, a wall extending between the boiler furnace and the mud drum, a plurality of plates extending edge to edge across the boiler and connected to the wall, each plate having a sliding contact with the headers, looped members extending through vertical slots in the plate and around the nipples and connected to the plates to hold the plates in contact with the headers, said plates having projections extending into the wall and arranged to permit relative vertical motion and to prevent relative horizontal motion between the plates and the wall, and a water trough beneath the mud drum and supported independently of the boiler and the wall and having a sliding contact with the lower edges of said plates.

HOWARD J. KERR.
